(57) **CLAIM**

The ornamental design for a inflation block for a balloon inflation device, as shown and described.

DESCRIPTION

FIG. 1 is a front elevational view of the device;

FIG. 2 is a top view;

FIG. 3 is a right side elevational view;

FIG. 4 is a left side elevational view;

FIG. 5 is a bottom view; and,

FIG. 6 is a rear elevational view.

The broken lines are included for the purpose of illustrating unclaimed portions of the inflation block, and form no part of the claimed design.

1 Claim, 2 Drawing Sheets

FIG.-2

FIG.-1
